FRANK W. ROBINSON, OF READING, PENNSYLVANIA, ASSIGNOR, BY MESNE ASSIGNMENTS, TO SCOTT AND WILLIAMS, INC., OF NEW YORK, N. Y., A CORPORATION OF MASSACHUSETTS

HIGH SPLICE ATTACHMENT FOR CIRCULAR KNITTING MACHINES

Application filed May 16, 1921. Serial No. 469,788.

My invention relates to circular knitting machines having a "high-splice" or extra-thread guide finger, and my particular object is to provide control means adapted to give any desired tapered outline to the high-spliced or reenforced portion of the knitting whereby the appearance of the finished fabric is improved. The invention is fully described in connection with the accompanying drawings and the novel features are pointed out in the claims.

Fig. 1 indicates, in front elevation, such portions only of a well-known type of knitting machine as are necessary to fully explain my invention, the needle cylinder being shown in cross-section.

Fig. 2 is a side elevation of the same, parts being broken away to more fully disclose the construction.

Fig. 3 shows the parts of my attachment in cross-section on the line 3—3 of Fig. 1; and Fig. 4 indicates a product of my improved machine.

Referring to the drawings, 5 represents the usual high-splice thread-guide finger which is normally spring-pressed to the lowered needle-engaging position shown and is raised to the non-engaging position indicated in dotted lines by a lever 6 connected by a rod 7 to a pattern-controlled lever 8 as usual. Heretofore during the high splicing operation, this finger 5 has been intermittently lowered and raised repeatedly alike for each revolution of the needle cylinder 10, so as to engage the reenforcing thread with a determined number only of the circular series of needles 12 to produce a uniform width of reenforced fabric. In my improved construction I provide for varyingly lowering and raising the finger 5 in successive revolutions of the needle cylinder so as to correspondingly vary the width of the reenforced fabric to produce an improved ornamental effect by tapering the reinforcement; this variation in the operation of the finger 5 being automatically accomplished as shown in the drawings, by the following mechanism:

Mounted in the machine frame are two short shafts, 20 and 30, the lower one being supported in bearings 21, 21 and carrying a

cam drum 22. The upper shaft 30 is mounted in bearings 31, 31 fastened to the table 32 and is partly screw-threaded at 33 as shown, to engage a travelling-nut member 34. The shaft 20 is driven from the main shaft 23 of the machine through a train of gears 24, 25, 26, 27 so as to be rotated with the same speed as the needle cylinder 10; and the shaft 30 is rotated, from shaft 20 by gears 28 and 35. The travelling-nut member 34 has a downward extension 36 forming a rocker arm arranged to ride upon the cam drum 22, and an upwardly inclined extension 37 which rests upon and travels along the upper straight edge 38 of a bar 39, which latter has inturned ends 40, 40 pivoted at 41, 41 to projecting ears 42, 42 of the bearings 31, 31; while a spring pressed finger 43 pivotally carried by extension 37 normally maintains the bar in contact with the latter. A rearwardly projecting arm 44 from the bar 39 is adapted to press upon a ledge 45 fastened to the connecting rod 7 to depress the latter and raise the guide finger 5 to inoperative position each time the travelling-nut member 34 is rocked by its arm 36. This travelling-nut member is used in connection with an upper nut member 34a which is alone threaded to engage the screw-threaded portion 33 of shaft 30, and has one end pivotally connected at 46 to the lower nut member 34 while its projecting other end 47 rests upon the straight upper edge of a front bar 48, which latter has inturned ends 50, 50 pivotally carried by ears 52, 52 of the bearings 31, 31. A link 53 pivotally connects the bar 48 to a pattern actuated lever 54 which latter periodically rocks said bar upon its pivots 51, 51 to open the parted nut 34a against the closing action of a spring 55; and when in this open position a spring 56 moves the nut 34 in a reverse direction to the movement imparted by the screw-threaded shaft 30. A reduced portion 30a of the shaft 30 acts as a lock for the travelling nut-half 34a, into which the latter falls at the end of its screw actuated movement, to remain fixed in this position until released by the pattern actuated lever 54 to the reverse movement of the spring 56. The cam 22 has a depressed surface 57 with diverging sides

58, 58 as shown, into which depression the end of the rocker arm 36 falls at each revolution of the drum; the narrow end 59 limiting the lowered needle engaging position of the guide finger 5 to a minimum number of 5 needles as indicated, but the number engaged being progressively increased as the travelling nut 34—34^a causes the rocker arm to move lengthwise of the drum. When the nut 34—34^a has moved to the end of the 10 screw-threaded portion 33 of shaft 30 and nut-half 34^a falls into the locking reduction 30^a, the rocker arm 36 has reached the maximum width of the depression and further rotation of the drum causes equal rocking movements for each revolution and consequently equal width of the reenforced fabric.

The operation of my improvement will be readily understood from the foregoing description, the pattern control mechanism as 20 heretofore, acting at the proper time upon lever 8 to lower the thread-guide finger 5 to needle engaging position, the intermittent movement of the latter for each revolution of the needle cylinder being performed by cam 25 drum 22 variously rocking the arm 36—37; the latter through bar 39 and its extension 44 depressing connecting rod 7 to actuate lever 6 to raise the finger 5 each time the rocker arm rides upon the high surface of the drum, 30 and permitting the spring lowered finger to return to needle engaging position when the rocker arm falls into the depressed portion of the drum. Where reenforced soles are desired, the rocker arm 36 is held in its locked 35 position at the end of the screw actuated position in shaft reduction 30^a, so that the rotating cam drum 22 will cause equal width reinforcement throughout the foot. At the end 40 of the reenforcement, or before the beginning of the next, the automatic pattern control mechanism is adapted to actuate lever 54, the latter through link 53 lifting bar 48 to release nut-half 34^a from its locked position 45 in shaft reduction 30^a to the action of return spring 56.

The shape of the depressed portion 57 determines the shape to be given the reenforcement, and may be varied as desired; and my 50 improvement may be readily applied to knitting machines without disturbing or interfering with their other automatic operations. Modifications in construction will obviously suggest themselves, the essential requirement 55 being the variable feed of the yarn to the needles during successive rotations of the needle cylinder 10. The desired operation of my improved machine provides for effecting 60 continuous circular knitting of a seamless tubular fabric with high-splice portions comprising reenforcing thread interwoven in successive courses for determinedly varied lengths only, and with unknitted free portions as in ordinary high-splicing.

What I claim is:

1. In a circular knitting machine having a movable extra-thread guide finger; means for automatically swinging said finger into and out of needle engaging position during 70 each of a series of rotations of the latter, said means comprising a drum having a peripheral cam surface extending longitudinally thereof a distance corresponding with the total spread of the courses knitted during 75 said series of rotations and a maximum circumferential extent corresponding approximately with that of a half-circle of needles, and a finger-swinging arm arranged to contact with a different portion of said cam surface at each rotation of the cylinder to determinedly vary the maintaining of said finger in needle-engaging position.

2. In combination with a circular knitting machine comprising a movable extra-thread guide finger, a rocker arm controlling the movement of said finger during each of a series of rotations of the needle cylinder, a rotating cam drum actuating said rocker arm, and means for relatively moving said 90 drum and arm at each rotation to determinedly vary the needle-engaging positioning of said finger.

3. In combination with a circular knitting machine comprising a movable extra-thread guide finger, a rocker arm controlling the movement of said finger during each rotation of the needle cylinder, a rotating cam drum actuating said rocker arm, and means for transversely moving said arm across the 100 face of the drum to vary the rocking movement in successive rotations.

4. In combination with a circular knitting machine comprising a movable extra-thread guide finger, a rocker arm controlling the movement of said finger during each rotation of the needle cylinder, a cam drum actuating said rocker arm, and means for reversely moving said arm transversely across the face of the drum.

5. In combination with a circular knitting machine comprising a movable extra-thread guide finger, a rocker arm controlling the movement of said finger during each rotation of the needle cylinder, a rotating cam drum actuating said rocker arm, means for positively moving said arm transversely across the face of the drum, and spring means for reversely moving the same.

6. In combination with a circular knitting machine comprising a movable extra-thread guide finger, a rocker arm controlling the movement of said finger during each rotation of the needle cylinder, a rotating cam drum actuating said rocker arm, means for positively moving said arm transversely across the face of the drum, locking means to retain the arm at the end of such movement, and spring means for reversely moving the arm upon release of the locking means.

7. In combination with a circular knitting machine comprising a movable extra-thread guide finger, a variable control device for said finger consisting of a swinging bar having a finger actuating arm, a screw-traversed rocker arm having one end slidably bearing on said bar and its opposite end movable lengthwise of a rotating drum, said drum having a diverging-wall cam surface adapted to variously rock said movable arm. 70
- 5 8. In combination with a circular knitting machine comprising a movable extra-thread guide finger, a variable control device for said finger consisting of a rotating drum having a diverging-wall cam surface, a swinging bar having a finger actuating arm, a screw-traversed rocker arm having one end slidably bearing on said bar and its opposite end movable lengthwise upon 75 said drum, a locking device to retain the arm at the end of its screw traversed movement, and a spring adapted to reversely move said arm upon release of said locking device. 80
- 10 9. In combination with a circular knitting machine comprising a movable extra-thread guide finger, a rocker arm controlling the movement of said finger during each rotation of the needle cylinder, a rotating cam drum actuating said rocker arm, means for relatively adjusting said arm and drum with each rotation, means for determinedly retaining the arm in desired finger-controlling position at the end of such adjusting movement, and means for returning said arm and drum to normal relative position. 85
- 15 10. In combination with a circular knitting stocking machine, means for intermittently raising and lowering the high splicing finger of the machine and means cooperating with said means for modifying the action of said means to cause said finger to be in operation for a successively increasing 90 period to thereby knit the high splice triangular in configuration. 100
- 20 11. A circular knitting machine, having needles and yarn guides, including a splicing yarn guide, a pattern mechanism and means whereby the latter may control the active and inactive positions of the yarn guides at different stages in the knitting in combination with an automatically variable cam adapted to control the active and inactive positions of the splicing yarn guide during each revolution of the knitting head. 105
- 25 12. A circular hosiery knitting machine, having needles and yarn guides, including a high splice yarn guide, in combination with means for producing a tapering high splice during round and round knitting, said means including a movable cam to throw said high splice yarn guide into and out of operative position once at each revolution and automatic devices to gradually vary the action of 110
- 30 said cam to throw said high splice yarn guide into and out of operative position for a gradually changing number of needles at different courses through the spliced area up to approximately half the circle of needles. 115
- 35 13. A circular hosiery knitting machine, having needles and yarn guides, including a high splice yarn guide, in combination with means for producing a tapering high splice, said means including a movable cam and automatic devices to gradually vary the action of said cam to throw said high splice yarn guide into and out of operative position for a gradually changing number of needles at different courses through the spliced area up to approximately half the circle of needles. 120
- 40 14. A circular hosiery knitting machine having needles and yarn supplying fingers including a high splice yarn finger in combination with means for bringing the high splice yarn finger and needles into and out of yarn engaging position, during round and round knitting, and means for gradually varying in different courses the number of needles supplied with high splice yarn, up to approximately a half circle of the needles, to thereby make the high splice tapering in configuration, with unknitted portions of the high splice yarn floated across the circle of needles at successive courses. 125
- 45 15. In a circular knitting machine having needles and yarn fingers including a high splice yarn finger in combination with means for automatically swinging said high splice yarn finger into and out of yarn feeding position during each of a series of rotations of the machine and means for variably maintaining said finger in needle-engaging position during successive courses to engage a gradually increasing number of needles up to a maximum of approximately a half circle of needles, to form a tapering high splice. 130
- In testimony whereof I affix my signature.
